UNITED STATES PATENT OFFICE

ALEXANDER FRANCIS McNISH, OF PERTH, SCOTLAND, ASSIGNOR OF ONE-HALF TO
JOHN MONCRIEFF LIMITED, OF PERTH, SCOTLAND

PADDLE MECHANISM FOR CIRCULATING MOLTEN GLASS

Application filed April 12, 1929, Serial No. 354,575, and in Great Britain June 1, 1928.

This invention has reference to improved paddle mechanism for circulating molten glass through the fore-hearth of a glass furnace or through any similar trough or channel.

The present invention consists in mounting the paddle holder on a horizontal fulcrum which is reciprocated vertically to raise and lower the paddle and to cause it to dip into the glass, whilst mechanism is provided to rock the paddle to and fro so that it travels in one direction in the glass and returns when raised out of the glass. By this construction the fulcrum can be so situated that it requires only a small opening in the cover of the fore-hearth for the passage of the paddle through the cover.

In order that the invention may be more clearly understood, reference is made to the accompanying drawings showing improved paddle mechanism according to this invention.

Fig. 1 is a vertical sectional view. Fig. 2 is a view at right angles thereto, showing the forehearth in section. Fig. 3 is a plan view.

The paddle 4 has a shank 5 which is carried by a paddle holder 6. The fulcrum consists of a pin 7 on the paddle holder journalled in a slide 8 guided vertically and reciprocated by means of a rotating cam 10. The paddle holder 6 is oscillated about its fulcrum 7 by means of a crank pin 11 which works in a slot 12 in the paddle holder.

The cam 10 is shaped to give the desired vertical stroke to the paddle 4 and preferably coacts with a roller 13 adjustably or otherwise mounted on the slide 8 which may be guided by means of fixed vertical guide rods 9 passing through cross heads 14 on the slide 8.

The throw of the crank-pin 11 determines the stroke of the paddle 4 in a horizontal direction and the cam 10 and crank-pin 11 are so situated in relation to one another that the paddle 4 is first dipped into the glass, then rocked in one direction about its fulcrum 7 to move the paddle through the glass in the trough or forehearth, whereupon the paddle 4 is raised out of the glass and finally rocked back again about its fulcrum 7.

The paddle holder 6 is preferably of in-

verted L-shape, its shorter horizontal limb supporting the core rod 15 of a clay or other refractory paddle which passes through a conical opening 16 formed in a block 17 of clay or other refractory material which closes the opening 18 in the cover 19 of the forehearth 20. The vertical limb of the paddle holder 6 is provided at a short distance from its upper end with the projecting horizontal fulcrum pin 7 and is formed at its lower end with the vertical slot 12 which cooperates with the crank pin 11 conveniently mounted on one side of the cam 10.

The roller 13 may be adjustably mounted on the slide 8 by fitting it on a back plate 21 adjustably bolted to the slide 8.

The cam 10 is mounted on a cam shaft 22 which is rotated by any convenient means and the cam 10 is shaped to give the desired height of stroke and dipping movement.

It will be noted also that the mechanism can be arranged outside the forehearth so that the paddle holder overhangs the outside wall of the forehearth.

Claims:

1. Mechanism for circulating molten glass through a trough comprising a paddle, a holder for supporting the paddle in the trough, a horizontal fulcrum for the paddle holder, means for reciprocating the fulcrum in a rectilinear vertical path, and means for rocking the holder about its fulcrum.

2. The combination with a molten glass circulating trough of a cover for the trough, said cover having an aperture therein, a paddle having a shank extending through said aperture, a holder attached to the shank of the paddle, a horizontal fulcrum for said holder, means for rocking the holder about its fulcrum and means for vertically reciprocating the fulcrum, said fulcrum being situated close to the level of said aperture so as to permit of the provision of only a small clearance between said aperture and the paddle shank.

3. A glass circulating trough having mechanism as specified in claim 2 wherein the fulcrum is situated just above the level of the aperture in the cover of the trough when the paddle is at its maximum height.

4. Mechanism for circulating molten glass

through a trough comprising a paddle, a holder for supporting the paddle in the trough, a horizontal fulcrum for the paddle holder, a vertically-guided rectilinearly movable slide supporting said fulcrum, and a rotary element for reciprocating said slide, said rotary element cooperating with the paddle holder to rock the latter about the fulcrum.

5. Mechanism for circulating molten glass through a trough comprising a paddle, a holder for supporting the paddle in the trough, a horizontal fulcrum for the paddle holder, a vertically-guided rectilinearly movable slide supporting said fulcrum, a rotary cam for reciprocating the slide and a rotary crank for rocking the paddle holder about its fulcrum.

6. Mechanism for circulating molten glass through a trough comprising a paddle, a holder for supporting the paddle in the trough, a horizontal fulcrum for the paddle holder, a vertically-guided rectilinearly movable slide supporting said fulcrum, a rotary cam for reciprocating the slide and a crank pin on said cam, said crank-pin cooperating with a slot in the paddle holder, to rock said paddle holder about said fulcrum.

7. Mechanism as specified in claim 4 wherein the rotary element cooperates with an adjustable member on the slide.

8. Mechanism for circulating molten glass through a trough comprising a paddle, a paddle holder consisting of a horizontal limb for supporting the paddle, a vertical member supporting said limb, a horizontal fulcrum for said member, means for reciprocating said fulcrum in a rectilinear vertical path, and means for rocking said member about its fulcrum.

40 9. Mechanism for circulating molten glass through a trough comprising a paddle, a paddle holder overhanging the trough, a slotted vertical member supporting said holder, a fulcrum pin extending horizontally from said member, a vertically-guided slide in which said pin is journaled, a rotary cam for reciprocating said slide, and a rotary crank-pin cooperating with the slotted member to rock the paddle holder.

50 In testimony whereof I have affixed my signature.

ALEXANDER FRANCIS McNISH.
